UNITED STATES PATENT OFFICE

91,694

DESIGN FOR A WEIGHING MACHINE CASING

Robert Vogel, Hamburg, Germany

Application September 25, 1933, Serial No. 49,337

Term of patent 3½ years

To all whom it may concern:

Be it known that I, ROBERT VOGEL, a citizen of Germany, residing at 21-41, Hammerstein-damm, Hamburg, Germany, have invented a new, original, and ornamental Design for a Weighing Machine Casing, of which the following is a specification, reference being had to the accompanying drawing, forming part thereof.

In the drawing,

Fig. 1 is a side elevational view of the weighing machine casing, showing my new design;

Fig. 2 is a perspective view thereof on an enlarged scale.

I claim:

The ornamental design for a weighing machine casing, as shown and described.

In testimony whereof I affix my signature.

ROBERT VOGEL.
